UNITED STATES PATENT OFFICE.

ROBERT SENFTNER, OF BROOKLYN, NEW YORK.

STATION-INDICATOR.

SPECIFICATION forming part of Letters Patent No. 392,693, dated November 13, 1888.

Application filed June 19, 1888. Serial No. 277,566. (No model.)

To all whom it may concern:

Be it known that I, ROBERT SENFTNER, a citizen of the United States, and a resident of Brooklyn, in the county of Kings and State of New York, have invented a certain new and useful Improvement in Station-Indicators, of which the following is a specification.

Letters Patent No. 352,576, of November 16, 1886, were granted to me for a station-indicator, which consists, essentially, of an indicator placed inside the car and the striking and indicator operating mechanism fixed to the body of the car, and also Letters Patent No. 379,292, of March 13, 1888, for improvements in the striking and indicator-operating mechanism.

My present invention relates to improvements in both the indicator and the striking and indicator operating mechanisms; and it consists, essentially, of the elements and combinations hereinafter set forth.

In the drawings, Figure 1 is a front elevation, partly in section, of my improved indicator. Fig. 2 is a top view of the same with the supporting-bar partly broken away. Fig. 3 is a perspective view of the striking and indicator-operating mechanism.

As will be seen by reference to my Patent No. 352,576, of November 16, 1886, the indicator-case A is suspended at or near the center of the car or in any other desirable place by means of the bar B. This case consists of a metal box through which a shaft, C, passes, having its bearings in the sides of the said case. A dial is placed on both sides of the box, and on the ends of the shaft C are rigidly affixed pointers C', which point to the various stations on the dial as the indicator is operated.

Rigidly attached to the shaft C are two ratchet-wheels, D D', having their respective teeth set in a direction exactly opposite to each other.

E E' are two levers, the enlarged or circular ends of which loosely surround the shaft C and are free to vibrate upon the same. Near the upper ends of these levers E E' are pivotally connected the pawls F F', having upwardly-extending arms a a', to which are connected the wires or cords b b', which are led oversuitable pulleys and guides down to each

of the indicator-operating mechanisms placed on each side of the car. The pawls F F' are located directly over the ratchet-wheels D D' and are provided at their forward ends with curved and downwardly-projecting contact-points c c', the rearward ends, d d', being extended so as to make those ends heavy enough to disengage the contact-points c c' from the teeth of the respective ratchet-wheels. If these extended ends are found to be insufficient to return the pawls F F' to their position of rest, a weight may be placed upon them.

On the upper flange of the case A are affixed two stops, G G', which extend down near to or in contact with the contact-points c c' of the pawls when the said pawls are in their normal position, and are so placed that they will deflect the points c c' of the pawls when they are operated into the teeth of their respective ratchet-wheels.

Fastened within the indicator-case A extending vertically across the same bridge, H, through which the shaft C passes. Attached to this bridge are two springs, I, only one of which is shown, located at or near the top and bottom of the ratchet-wheels D, and which acts as a detainer or detent to the revolution of either of the ratchet-wheels, (both being fastened to the same shaft or spindle,) and which prevents the further revolution or movement of the same after they have been operated by the pawls.

The levers E E' are respectively provided with springs e e', one end of each being fastened to pins or projections f f' on the supporting-plate B, the said springs returning the levers E E' to their normal position, as shown in the drawings, and at the same time withdrawing the pawls F F' from the radius of their respective ratchet-wheels.

As shown in the drawings, the indicator-system, comprising the ratchet-wheel D', lever E', pawl F', cord b', and spring e', composes, when put in operative combination with its striking and indicator-operating mechanism, an individual system, which may work irrespective of the other parts of the indicator mechanism, and is so designed that the automatic indication of every station will be insured. In this view the pawl F' is supposed

to be just about to enter into a tooth of the ratchet-wheel D', partly illustrating its operation.

Reference will now be had to Fig. 3, which 5 illustrates the striking and indicator-operating mechanism.

In actual use I place a striking and indicator-operating mechanism on both sides of the car at or near its center and connect them 10 with the indicator by means of cords or wires.

J is a supporting-plate, preferably attached to the floor of the car by means of the bolts or screws g g.

K is a cam pivotally attached by means of 15 the bolt h to the supporting-plate J. The cam K has a downwardly-extending arm, L, articulated at i, the lower portion, L', of said arm being extended downward a suitable distance to enable it to come in contact with 20 and ride over the stationary striking-blocks j, arranged at suitable places along the line of track. The arm L has a slot cut in its lower-most portion, which ends in the angular face k, against which the angular shoulder l of the 25 striking-lever L' bears. The lever L' is provided on its end with a sheet of rubber, M, or other flexible material, which acts as a resistance-piece to the stroke of the striking-lever, lessening the force of the stroke, thereby avoiding 30 any chance of a rebound and consequent double indication. A slot, m, is cut in the rubber M, through which passes a set-screw, n, by means of which the shortening of the rubber, caused by its wearing away by riding 35 over the striking-block, is compensated for. Instead of using the rubber M, I can form the whole lower portion of the striking-lever L' of iron or other suitable material, and do not, therefore, limit myself to the use of the rubber 40 sheet M alone.

The supporting-plate J is provided with a circular slot, o, in which is adjustably pivoted a bell-crank lever, N, carrying a roller, O, said 45 lever N being so pivoted in the slot o as to bring the roller O within the periphery of the cam K. The free end of the roller N is connected directly to the indicator by means of the flexible cord b, the same being carried up into the car over suitable pulleys to the indicator, 50 thus putting the striking and indicator-operating mechanism into operative connection.

The cam K and lever N are provided with springs p p', suitably screwed, which return them to their position of rest after being operated.

55 Fastened to the supporting-plate J is a cushion or pad, P, which receives the return blow of cam K.

Having thus described the nature of my invention, I will now proceed to describe its operation.

As before stated, the striking-blocks j are placed at suitable places along the line of track, and the striking-lever L', being properly 65 adjusted in relation to said block, will, when it encounters the same, ride over it, at the same time, by means of the shoulder l of the

lever L' bearing against the inclined face k, vibrating the cam K, which in its turn bears against the roller O on the lever N, vibrating 70 the same, setting in motion the cord b, leading up to the indicator. The cord b, being connected with the pawl F, draws it and lever E forward, the front end of the pawl striking the stop G, by which it is deflected down into a tooth of 75 the ratchet-wheel, thereby rotating the same. The ratchet-wheels being fast upon the spindle C, and upon which the pointers C' C' are also affixed, rotates them with it, undue rotation being prevented by the action of the spring 80 I upon the ratchet-wheel. After the lever L' has passed entirely over the striking-block j it will be returned to its position of rest by the spring p', the return blow being received by the cushion P. When the lever L' assumes 85 the position shown in the drawings, the pressure being thus relieved from the lever N, the spring p will then return it to its position of rest, slackening the cord b and permitting the spring e on the indicator and the weighted 90 arm d of the pawl F to co-operate in withdrawing the contact-point of said pawl from within the radius of the ratchet-wheel.

It will be obvious that if another and similar striking and indicator operating mechanism were placed on the body of the car, opposite to the one shown and described, and if a striking-block was properly arranged to vibrate the striking-lever, the other set of indicator parts would thereby be operated, 100 and when a car is so provided with duplicate striking and indicator-operating mechanisms, and they are properly connected with the indicator, the automatic indication of the stations must necessarily take place even though 105 the car run back and forth over the same striking-blocks any number of times, and in the event of the car being completely turned around the automatic indication of the stations will still take place.

As it is intended that but one set of mechanism shall be operated at one time, the striking-blocks are fixed in a reversed direction on either side of the track, so that when the striking-lever that is not to set its own system in motion, or, in other words, that is not to operate, strikes the abrupt portion j" of the striking-block it will cause the lower portion, L', to vibrate at its point of articulation with the arm L, thus permitting that indicator system 115 to pass over the striking-block unoperated.

The lateral or vertical motion of the car will not in the least affect the operation of my indicator, the articulated arm L L' and the rubber sweeper M compensating for any of these 125 motions.

I do not confine myself to the particular form and arrangement of details shown, but may change or alter them to suit particular circumstances and conditions.

Having thus described the nature and operation of my invention, what I claim, and desire to secure by Letters Patent, is—

1. In a station-indicator, a ratchet-wheel

mounted upon a rotating shaft, a lever pivotally secured to said shaft and provided with a spring to return it to its normal position, a pawl secured to and vibrating independently of said lever, and a stop for deflecting the said pawl into the teeth of the ratchet-wheel, in combination with means for operating the same, the operating means being connected directly with the said pawl, substantially as described.

10c 2. In a station-indicator, a ratchet-wheel mounted upon a rotating shaft, a vibrating lever pivotally secured to said shaft and provided with a spring to return it to its normal position, a pawl secured to and vibrating independently of said lever, and a stop for deflecting the said pawl into the teeth of the ratchet-wheel, in combination with a striking mechanism comprising a cam and lever pivotally secured to the body of the car, and a vibrating 15 arm in operative connection with the said cam, the said arm being operatively connected with the pawl of the indicating mechanism, substantially as described.

3. In a station-indicator, a ratchet-wheel 25 mounted upon a rotating shaft, a vibrating lever pivotally secured to said shaft and provided with a spring to return it to its normal position, a pawl secured to and vibrating independently of said lever, and a stop for deflecting the said pawl into the teeth of the ratchet-wheel, in operative combination with an adjustably-pivoted lever operated by a cam pivotally secured to the body of the car, and an 30

articulated striking-lever secured to said cam, substantially as described.

4. In a station-indicator, a ratchet-wheel mounted upon a rotating shaft, a vibrating lever pivotally secured to said shaft, a pawl secured to and vibrating independently of said lever, and a stop for deflecting the said pawl into the teeth of the ratchet-wheel, in combination with the weighted arms of the pawls, springs connected with the vibrating lever to return it to its normal position, and means for operating the same, substantially as described.

5. In a station-indicator, the indicating mechanism comprising ratchet-wheels D and D', mounted upon a rotating shaft, C, levers E and E', mounted to vibrate upon the shaft C, and pawls F and F', mounted to vibrate upon the levers E and E', operatively combined with a striking mechanism comprising a lever, N, cam K, and articulated striking-lever L and L', substantially as described.

6. In a station-indicator, the combination, 55 with the ratchet-wheels D and D', mounted upon the rotating shaft C, levers E and E', mounted to vibrate upon the shaft C, and pawls F and F', mounted to vibrate upon the levers E and E', of the weighted arms d and d' of the 60 pawls, and springs e and e', attached to the levers E and E', substantially as described.
